J. M. YATES

HANDLE FOR MOTOR VEHICLE DOORS AND THE LIKE

Filed June 3, 1922

FIG. 1

FIG. 2

FIG. 3

INVENTOR

J. M. YATES

By Chindell Parker Tolson
ATTYS.

UNITED STATES PATENT OFFICE.

JOSEPH M. YATES, OF CHARLOTTE, MICHIGAN, ASSIGNOR TO HANCOCK MANUFACTURING COMPANY, OF CHARLOTTE, MICHIGAN, A CORPORATION OF MICHIGAN.

DESIGN FOR A HANDLE FOR MOTOR VEHICLE DOORS AND THE LIKE.

Application filed June 3, 1922. Serial No. 2,511. Term of patent 3½ years.

To all whom it may concern:

Be it known that I, JOSEPH M. YATES, a citizen of the United States, residing at Charlotte, in the county of Eaton and State of Michigan, have invented a new, original, and ornamental Design for Handles for Motor Vehicle Doors and the like, of which the following is a specification, reference being had to the accompanying drawings, forming part thereof.

Figure 1 is a side elevation of a handle embodying my new design. Fig. 2 is a front or plan view of the handle. Fig. 3 is an end view of the same.

The dominating feature of the design is the ornamental effect obtained by the use of polished metal inlays embedded in the cross-piece of the handle, and having an exposed polished face, the handle proper being made of hard rubber or other suitable material.

I claim:

The ornamental design for a handle for motor vehicle doors and the like, substantially as shown.

JOSEPH M. YATES.
